INVENTOR.

WILLIAM C. HASHA.

BY *H. A. Duckman*
ATTORNEY.

UNITED STATES PATENT OFFICE.

WILLIAM C. HASHA, OF LONG BEACH, CALIFORNIA.

WASHING MACHINE.

Application filed September 17, 1925. Serial No. 56,883.

This invention relates to a clothes washing machine, and an object is to provide a machine whereby the clothes will be washed by the gentle dropping thereof from one shelf in the clothes cylinder into an adjacent shelf, and then on to the bottom of the cylinder, and thereafter picked up by shelves and again subjected to such dropping and in which the clothes while so dropped will be subjected to a forcible stream of air and water, with the result that the finest fabrics may be thoroughly washed without injury thereto and in an expeditious manner.

Another object is the provision in a washing machine of a combined air and water circulating pump, for forcibly ejecting the fluid against clothes which are arranged in a slowly revolving cylinder, the latter having therein spaced angled shelves.

A further object is to provide a washing machine, with compartments in which the wash and rinse water may be stored while not in use, such water being readily available when needed.

A still further object is to provide a washing machine embodying the above mentioned objects, which is simple in construction, inexpensive to manufacture, and efficient in operation.

Other objects, advantages, and features of invention may appear from the accompanying drawing the subjoined detailed description and the appended claims.

In the drawings illustrating my invention. Fig. 1 is a longitudinal sectional view of my washing machine.

Fig. 2 is a sectional view on line 2-2 Fig. 1.

Fig. 3 is a sectional view on line 3-3

Fig. 4. is a sectional view on line 4-4

Fig. 5. is a fragmentary end view of one of the manual control valves.

Referring more particularly to the drawing, my washing machine comprises a housing 10, substantially rectangular in form, and having a front wall 11, and a rear wall 12. The housing 10 is supported on wheeled legs 13. A vertical wall 14 extends transversely through the housing and rises from the bottom thereof to a horizontal shelf 15, thus forming a pump compartment 16. A vertical wall 17 rises from the shelf 15 to

the top of the housing 10 and forms the

motor compartment 18. A horizontal wall 19 is spaced from the bottom of the housing, and in conjunction with the walls 14, 17 and the sides of the housing forms the washing compartment 20.

A vertical partition 21 rises from the floor of the housing to the wall 19 and forms the tanks 22 and 23, the purpose of which will be further described.

Arranged centrally on the face of the wall 14 within the compartment 20 there is a conduit 24.

A hollow clothes washing cylinder 25 is revolvably mounted in the compartment 20, and is formed with a hollow axial hub 26, which extends into the conduit 24, and is journaled in the walls thereof. From the other side of the cylinder a pintle 27 extends which is journaled in the rear wall 12. The cylinder is provided with a door 28, to give access to the interior thereof. Secured or formed in the inner periphery of the cylinder, there are equidistantly spaced angularly disposed shelves 29, preferably four in number. As shown in Fig. 3, the shelves are substantially V shaped in cross section, and the pointed ends thereof are directed in a line approximately normal to the adjacent shelf. The outer ends of the shelves may be corrugated as at 30 which tends to retard the movement of the clothes in leaving the shelf and also tumbles said clothes as they drop. Holes 31 are provided in the wall of the cylinder 25 to provide egress for the water.

A cylindrical water and air pump 32 is revolvably mounted in the compartment 16, and is secured to a shaft 33 which is journaled in the wall 11 and in the wall of the conduit 24. A hollow hub 34 surrounds the shaft 33 and protrudes from the side of the pump 32 into the conduit 24 and is journaled in the wall 14. This hub also communicates with the center of the pump as will be further described. The pump 32 is formed with two spiral passages 35, 36 which extend from diametrically opposed peripheral intake ports 37, 38 respectively, and both passages terminate at the center and communicate with the hub 34.

An electric motor 39 is mounted on the shelf 15. A gear 40 is secured to the shaft of the motor, and meshes with a gear 41 secured to a horizontal shaft 42, which shaft is journaled in the walls 11 and 17. A vertical shaft 43 extends through the top of the

washing machine and is driven by gearing 44 from the shaft 42. Suitable gearing 45 on the shaft 43 drives a wringer 46. The wringer and gear drive therefor is of well known construction and need not be described in detail.

A gear 47 on the shaft 42 meshes with an idler gear 48 and the idler gear meshes with a gear 49 secured to the shaft 33 thereby rotating said shaft and pump 32.

A spur gear 50 is secured to the inner end of the shaft 33 which meshes with a ring gear 51 secured to the side of the cylinder 25. The ring gear 51 is concentric with the axis of rotation of the cylinder 25. The ratio of the gears 50, 51 is such that the cylinder 25 is slowly rotated in one direction about 8 or 10 revolutions per minute more or less.

20 A throw-out clutch 52 is provided for the cylinder 25, which comprises a handle 53 pivoted to a bracket 54, and formed with a forked end which engages the grooved end 55 of the pintle 27. Thus the cylinder may 25 be shifted on its bearings to disengage the gears 50, 51.

A hand operated valve 56 is positioned in the conduit 24 between the hubs 26, 34, and is adapted to close said conduit. A stem 57 30 extends from the valve 56 through the outer wall of the housing 10, and a handle 58 on the outer end of the stem provides means to operate the valve.

35 A pipe 59 extends from the compartment 20 to the pump compartment 16, and provides a return flow means for the water from the compartment 20 to the compartment 16. A hand control valve 60 is mounted in said pipe. The control for the valve 40 is shown in Fig. 5 and consists of a stem 61 protruding through the side wall of the housing 10, and operable by a handle 62. The valves in each of pipes hereinafter described are identical with the valve 60 and 45 a detailed description of each one will not be given.

A pipe 63 extends from the bottom of the conduit 24 into the tank 22, and a hand controlled valve 64 is positioned therein. 50 A drain pipe 65 extends from the pipe 63 to the outside of the washing machine and a valve 66 is provided therein. A pipe 67 extends from the pipe 65 to the tank 23, and a valve 68 is positioned therein. A drain pipe 69 extends from the bottom of the tank 22 into the compartment 16, and a control valve 70 is provided therein. An outlet pipe 71 extends from the pipe 69 and a valve 72 is provided therein. A drain pipe 73 extends from the bottom of the tank 23 to the pipe 69, and a valve 74 is provided therein.

In operation the pump 32 is rotated by the motor 39, through the gears 40, 41, 47, 65 48 and 49. Water is provided in the com-

partment 16, and stands therein to a point about level with the wall 19. Rotation of the pump causes air and the water to enter ports 37, 38, and the water passes thru the passages 35, 36 to the center and is forced out of the hub 34 into the conduit 24, thence through the hub 26 into the cylinder 25 and against the clothes therein. The water is returned to the compartment 16 through the pipe 59.

75 The slow rotation of the cylinder 25 causes the clothes to tumble from shelf to shelf thus presenting all sides thereof to the stream of air and water. Rinse or bleaching water may be retained in the tank 23, 80 and by closing valve 56 opening valve 64 and operating the pump, the wash water is forced into tank 22. Then opening valve 74, will drain the rinse water from tank 23 into compartment 16, where it is forced 85 through the clothes as previously described. The rinse water is returned to tank 23 by closing valve 56, opening 68, and operating the pump 32.

90 Having described the invention I claim:

1. In a washing machine, a clothes receiving cylinder comprising V shaped shelves therein, said shelves having corrugations thereon and each shelf having its outer and pointed end disposed normal to the adjacent shelf, means for slowly revolving the cylinder to permit the clothes to drop from one shelf onto the adjacent shelf and from the latter onto the bottom of the cylinder and means for injecting a washing fluid through the center of the cylinder and against the clothes in said cylinder.
